UNITED STATES PATENT OFFICE.

JOSEPH H. PRIM, OF SAGINAW, MICHIGAN, ASSIGNOR OF ONE-FOURTH TO FLOYD E. PRIM, OF SAGINAW, MICHIGAN.

VACUUM-SUPPORTING DEVICE.

Application filed May 31, 1921. Serial No. 473,759.

To all whom it may concern:

Be it known that I, JOSEPH H. PRIM, a citizen of the United States, residing at Saginaw, in the county of Saginaw and State of Michigan, have invented certain new and useful Improvements in Vacuum-Supporting Devices; and I do hereby declare the following to be a full, clear, and exact description of the invention, such as will enable others skilled in the art to which it appertains to make and use the same.

This invention relates to vacuum supporting devices and pertains more particularly to that class of supporting devices wherein spring arms project from a vacuum cup and the arms engage the glass plate or other surface to which the cup is secured.

My improvement relates more particularly to the construction and mode of operation of the spring arms in combination with a vacuum cup.

The improvement includes a spring arm structure that is simple and inexpensive and capable of being stamped from a single piece of sheet metal.

My improved spring arm construction also comprises a fastening arrangement whereby the arms can be quickly and securely fastened to the vacuum cup. The arms also are provided with means whereby any arm may be raised independently of the others, and are also provided with means whereby threads or cords can be quickly attached to the arms, for use in arranging window decorations and for similar purposes.

With the foregoing and certain other objects in view, which will appear later in the specification, my invention comprises the devices described and claimed and the equivalents thereof.

In the drawings, Fig. 1 is a top plan view of my improved vacuum supporting device.

Fig. 2 is a central vertical section taken on the line 2—2 of Fig. 1.

In the drawings, 1 represents a vacuum cup of rubber or other suitable material and 2 is a central boss formed integral therewith, the boss being formed with a circumferential groove 3. The spring arm structure comprises an apertured plate 4 which when assembled on the vacuum cup 1 is received in the groove 3. The plate 4 has a plurality of laterally extending spring arms 5, the ends of which curve downwardly and termi-

nate in elongated feet 6, the edges of these feet engaging the plate of glass or other surface to which the vacuum cup may be secured.

Each of the feet 6 is preferably provided with a projection 7 which may be struck up from the metal of the plate to form a niche into which the finger nail may be inserted to lift the foot 6 so that a sheet of paper or other article to be attached to the holding surface may be inserted beneath the foot.

Similarly a hook 8 is formed by striking up the metal of the arm. This hook is adapted to receive a thread or string which may thus be anchored to the holding surface.

To firmly hold the plate 4 in position on the boss 2, I provide a hook, eyelet, knob or similar device 9 having a shank 10 terminating in a flange 11 and carrying a washer 12.

The shank 10 and flange 11 are preferably molded into and thereby formed integral with the boss 2. The washer 12 is preferably flanged upwardly around its periphery as shown in Fig. 2, so that a string or flexible cord 13 may be anchored thereto by passing the cord under the edge of the washer 12, thereby wedging it between the top of the boss 2 and the edge of the washer.

The outside diameter of the washer 12 is preferably such as to permit the washer to be passed through the central opening of the plate 4. The plate 4 may be secured to the rubber boss 2 by forcing the plate downwardly over the washer 12 until the edge of the central opening of the plate is received in the annular groove 3 of the boss 2, as shown in Fig. 1.

Washer 12, being of almost the same size as the opening in plate 4, will prevent the plate from being removed from the boss 2, because of the resistance to shearing of the top part of the rubber boss 2, thereby securely locking the plate 4 in place in the groove of the boss.

By the means above described, I have produced a simple and inexpensive vacuum supporting device in which the spring arms are provided with anchorages for cords and each arm is provided with independent lifting means. The central plate which carries the plurality of arms is assembled with and firmly anchored to the central boss of the

vacuum cup by merely pressing the plate down over the washer, said washer also forming an anchorage for a cord.

Having thus described my invention, what I claim and desire to secure by Letters Patent is:

In a vacuum supporting device including a vacuum cup formed with a boss, a spring metal plate, said plate formed with four outwardly and downwardly projecting spring arms thereon, each arm formed with a lat-

erally projecting elongated foot, each foot formed with a lifting niche therein, and a hook on said plate near one end of each of said spring arms, a washer received on said boss, the circumferential edges of said washer flanged upwardly and adapted to receive and wedge a cord between said washer and the top of said boss.

In testimony whereof, I affix my signature.

JOSEPH H. PRIM.
